UNITED STATES PATENT OFFICE.

HARRY EUGENE HALL, OF SCRANTON, PENNSYLVANIA

ARTIFICIAL TOOTH AND BACKING THEREFOR.

1,182,560.

Patented May 9, 1916.

Application filed September 8, 1915. Serial No. 49,565.

To all whom it may concern:

Be it known that I, HARRY EUGENE HALL, a citizen of the United States, residing at Scranton, in the county of Lackawanna and

60

5 State of Pennsylvania, have invented new and useful Improvements in Artificial Teeth and Backings Therefor, of which the following is a specification.

The invention relates to an artificial tooth 10 and backing therefor.

The primary object of the invention is the provision of a tooth and backing therefor wherein the artificial tooth can be readily and easily placed in position and 15 firmly held upon the backing, the backing being novel in form to permit the securing of the tooth within the mouth, yet it may be interchanged when the occasion requires.

Another object of the invention is the provision of an artificial tooth and backing therefor wherein the possibility of the displacement of the tooth upon the backing is eliminated, and maximum strength is had both in the backing and the tooth.

25 A still further object of the invention is the provision of an artificial tooth and backing therefor wherein the said tooth has two ground flat surfaces at right angles to each other and also a pair of triangular openings 30 for accommodating a right angled metallic backing, which is formed with a tongue diverging from the meeting of the right angles and shaped to engage in the openings for the interchangeable mounting of the 35 tooth upon the backing.

A still further object of the invention is the provision of an artificial tooth and backing therefor which are simple in construction, thoroughly reliable and efficient, 40 strong, durable, and inexpensive in manufacture.

With these and other objects in view, the invention consists in the construction, combination and arrangement of parts as will be 45 hereinafter fully described, illustrated in the accompanying drawing, and pointed out in the claim hereunto appended.

In the drawing:—Figure 1 is a side elevation of an artificial tooth and backing therefor constructed in accordance with the invention. Fig. 2 is a vertical longitudinal sectional view thereof. Fig. 3 is a perspective view of the backing with the tooth removed. Fig. 4 is a perspective view of the tooth removed from the backing. Fig. 5 is 55 a side elevation of a slightly modified form

of tooth and backing. Fig. 6 is a longitudinal sectional view thereof. Fig. 7 is a perspective view of the tooth removed from the backing.

60

Similar reference characters indicate corresponding parts throughout the several views in the drawing.

Referring to the drawing in detail, A designates an artificial tooth which is 65 ground to form flat surfaces 10 and 11, respectively, at substantially right angles to each other, while opposite sides of the said tooth are formed with substantially triangular shaped openings 12 whereby the 70 tooth can be interchangeably fitted upon the backing hereinafter fully described.

The backing comprises a right angled plate 13, preferably made from platinoid, platinum, gold, or a combination 75 of gold and platinum, and from the meeting angle of this plate 13 diverges a tongue 14 which is cut to provide a V-shaped opening 15 therein forming pointed spurs or tips 16 which are adapted to engage in the triangular shaped openings 12 formed in the sides of the tooth A for the interchangeable connection thereof with the backing.

It is of course understood that the tooth is made from porcelain and is readily interchangeable so that it is adaptable for crown- 85 and bridge work, the flat surfaces 10 and 11 of the tooth being designed to rest against the angular portions of the plate constituting the backing therefor.

90

In Figs. 5, 6 and 7 there is shown a slight modification of tooth B which is ground to form the flat surfaces 17 and 18, respectively, at right angles to each other, and also cut to provide the triangular 95 shaped openings 19 in opposite sides thereof to receive the spurs 20 which diverge from the meeting of the right angles of the backing for supporting the said tooth, the spurs 20 being disposed at a different angle from 100 the angle of the tongue 14 hereinbefore described.

From the foregoing description, taken in connection with the accompanying drawing, the construction of the device will be clearly 105 understood, and therefore a more extended explanation has been omitted.

What is claimed is:—

An artificial tooth and backing therefor comprising a tooth having a cut away portion formed with flat surfaces at right angles to each other and also having tri-

110

angular openings at the meeting of the two cut away portions of the tooth and at an angle thereto, and a right angled shaped plate constituting a backing and having a tongue diverging from the meeting of the right angles and cut to provide spurs engageable in the openings in said tooth.

In testimony whereof I affix my signature in presence of two witnesses.

HARRY EUGENE HALL.
